(57) CLAIM

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon showing my new design; and,

FIG. 2 is a front view of a second embodiment thereof.

The broken lines around the Figures showing a display screen or portion thereof form no part of the claimed design.

FIG. 2

UNITED STATES PATENT AND TRADEMARK OFFICE
CERTIFICATE OF CORRECTION

PATENT NO. : D710,382 S
APPLICATION NO. : 29/424254
DATED : August 5, 2014
INVENTOR(S) : Imran Chaudhri

It is certified that error appears in the above-identified patent and that said Letters Patent is hereby corrected as shown below:

Delete title page and substitute therefore with the attached title page consisting of the corrected illustrative figure.

In the Drawings

Delete Drawing Sheet consisting of FIGS. 1 and 2 and substitute therefore with the attached Drawing
Sheet consisting of FIGS. 1 and 2.

Signed and Sealed this
Twenty-sixth Day of May, 2015

Michelle K. Lee
Director of the United States Patent and Trademark Office
